UNITED STATES PATENT OFFICE.

FRANK M. MIELKE, OF DULUTH, MINNESOTA.

RECEPTACLE.

Application filed May 1, 1922. Serial No. 557,574.

To all whom it may concern:

Be it known that I, FRANK M. MIELKE, a citizen of the United States, residing at Duluth, in the county of St. Louis and 5 State of Minnesota, have invented certain new and useful Improvements in Receptacles, of which the following is a specification, reference being had therein to the accompanying drawing.

10 This invention relates to receptacles and has special reference to a novel form of leader box for use by fishermen.

The principal object is to produce a watertight receptacle in which the leaders 15 may be kept in moist condition and yet convenient of access.

Other objects and advantages of the invention will appear in the further description thereof.

20 Referring to the accompanying drawing:

Figure 1 is a central vertical sectional view of one of the improved boxes having a plurality of coils of leaders therein, and

25 Figure 2 is a side elevation of the closed box.

The receptacle is circular in plan view and of a size convenient for carrying about in one's pocket.

The preferred embodiment of the invention 30 contemplates two separable portions, the body portion 1 and the closure portion 2; the former having an inwardly projecting annular rim 3 which is internally screw threaded, and the latter has an annular depending flange 4 which is externally screw 35 threaded near the base thereof for cooperative engagement with the rim 3. This flange 4 extends a considerable distance into the receptacle beyond its screw threaded portion as it is desirable to have only two or three threads for convenience in applying 40 or removing the cover.

Carried within the body portion 1 is a 45 felt or other similar absorbent disc 5 which is larger in diameter than the rim 3, and designed to fit within the body portion 1 beneath said rim. A second disc 6, of like material to the disc 5, is removably carried within the box, and, between these discs is 50 where the coils of leaders are carried, they being indicated at 7.

It is well known to those versed in the art of angling that it is very desirable to keep the leaders which are to be used 55 slightly moist, and to accomplish this the

discs 5 and 6 are moistened and the leaders carried therebetween in the box, and the cover 2 of the box, having a sufficiently deep flange 4 to slightly engage the disc 6, the edge of which normally rests upon the disc 7, will tend to retain the leaders intermediate of the discs in the interior of the box and thus keep quite damp for a long period of time.

In the preferred construction of box the 65 uppermost edge or rim 3 is milled or ground as are the engaging edges of the cover 2 so that a ground joint results intermediate of the cover and the body portion, so as to secure a tight joint, it being preferred 70 to construct the box of cast metal such as aluminum or the like.

The circumferential edge of the cover portion 2 extends slightly beyond the side walls of the body portion 1 and is knurled 75 as at 8 for convenience in screwing on and off, and a similar projection indicated at 9 is formed about the lower edge of the body portion and is also knurled, thus making a receptacle which is easily manipulated 80 regardless of one's hands happening to be damp or cold as the case may be.

Having thus described my invention what I claim and desire to secure by Letters Patent, is:

1. A leader receptacle comprising in combination two screw threadedly united cylindrical members, the circumferential walls of the body portions of said members being spaced one from the other forming an inner 85 annular space approximately the depth of the box intermediate thereof, two absorbent discs slightly smaller than the interior of the larger or female member of the receptacle and of sufficient thickness to be forcibly held together about the circumferential edges by the impinging of the male member of the receptacle when the latter is assembled, thus forming a leader receiving space intermediate of the discs which is 90 tightly sealed circumferentially.

2. A leader receptacle comprising two short telescopic screw threadedly united cylinders, each of said cylinders being closed at one end forming the opposite ends 100 of the receptacle when united and said closed ends projecting beyond the walls of the receptacle circumferentially, an annular space formed within the receptacle intermediate of the walls of the two parts there- 105 110

of, two absorbent discs within the receptacle for the reception of leaders therebetween, said discs being of sufficient thickness to be tightly impinged intermediate of the inwardly projecting walls of the male member of the receptacle and the end wall of the female member, substantially as described.

In testimony whereof I hereunto affix my signature in the presence of two witnesses.

FRANK M. MIELKE.
